(57) **CLAIM**

The ornamental design for a beverage thermal insulator, as shown and described.

DESCRIPTION

FIG. 1 is a top perspective view of a beverage thermal insulator;

FIG. 2 is a front view of the beverage thermal insulator;

FIG. 3 is a rear view of the beverage thermal insulator;

FIG. 4 is a right side view of the beverage thermal insulator;

FIG. 5 is a left side view of the beverage thermal insulator;

FIG. 6 is a top view of the beverage thermal insulator;

FIG. 7 is a bottom view of the beverage thermal insulator;

FIG. 8 is a bottom perspective view of the beverage thermal insulator; and,

FIG. 9 is a side perspective view of the beverage thermal insulator.
